G. J. FOX

SPARK ARRESTER AND SMOKE ELIMINATOR

Filed Sept. 29, 1922

Fig. 2.

ON LINE. 2-2. FIG. 1.

INVENTOR:
George J. Fox.
BY
Hudson Fairbanks.
ATTORNEYS.

UNITED STATES PATENT OFFICE.

GEORGE J. FOX, OF PHILADELPHIA, PENNSYLVANIA.

SPARK ARRESTER AND SMOKE ELIMINATOR.

Application filed September 29, 1922. Serial No. 591,218.

My invention consists of a novel construction of a spark arrester and smoke eliminator, which is adapted to be readily attached to cupola stacks and smoke stacks or the like, of any character, whereby I am enabled, by the installation of my device to eliminate sparks, oxides and carbon from the fumes emitted from said stack, said fumes being caused by my novel apparatus 10 to pass through a curtain or wall of water of such a character that sparks, oxides, carbon and the like will be entrapped within the arrester whereby the waste gases which finally emerge from my novel apparatus are 15 purified of certain deleterious elements or impurities.

To the above ends my invention consists of a novel construction of a casing having an upper outlet for the purified gases, below 20 which I locate means for creating the curtain or wall of water which is received in a suitable lower receptacle provided with a drain pipe, and an overflow, so that the apparatus is at all times automatic in its operation after having once been installed in 25 position with respect to the stack.

It further consists of other novel features of construction, all as will be hereinafter fully set forth.

30 For the purpose of illustrating my invention, I have shown in the accompanying drawing a form thereof which is at present preferred by me, since it will give in practice satisfactory and reliable results, although 35 it is to be understood that the various instrumentalities of which my invention consists can be variously arranged and organized and that my invention is not limited to the precise arrangement and organization of 40 these instrumentalities as herein shown and described.

Figure 1 represents a vertical sectional view of a spark arrester and smoke eliminator embodying my invention, certain of 45 the parts being shown in elevation.

Figure 2 represents a section on line 2—2
Figure 1.

Figure 3 represents a sectional view of another embodiment of my invention which 50 may be employed.

Similar numerals of reference indicate corresponding parts in the figures.

Referring to the drawings.

In carrying out my invention which is

adapted to be applied to the upper portion 55 of a cupola stack or smoke stack as 1, I employ an outer casing 2, which is preferably circular or annular in contour and which is provided at its lower portion with a base member 3, the inner portion of said 60 base member fitting nicely around the upper portion of the smoke stack 1, and being supported with respect thereto by any suitable means, as angle irons or brackets 4, or the 65 like.

The annular casing member 2 may be prolonged downwardly to form the lower conical member 5, whose lower end as indicated at 6 contacts with and incloses the stack 1, so as to give the upper portion of 70 the latter a neat and finished appearance, when my invention is installed thereon.

The base member 3 is provided with a port 7 which leads to a drain pipe 8 and the casing 2 is provided with an overflow 75 port 9, whose location will be understood from Figure 1.

10 designates an inner annular vertical wall, which is supported upon the base member 3 and secured with respect thereto by 80 the outer annular L-iron or angle iron 11 and the inner annular L-iron or angle iron 12, the lower edge of said wall 10 being riveted or otherwise secured to said angle 85 irons.

The junction of the outer edge of the base member 3 with the lower inner surface of the vertical outer wall 2 is also provided with an annular L-iron or angle iron 13 and I preferably caulk the upper edges of 90 the annular angle irons 11 and 13, so that an annular water tight chamber, which I have designated as 14 is formed between the outer upright wall 2, the horizontal base member or wall 3 and the inner wall 10. 95

For the purpose of reinforcing the upper edge of the inner wall 10, I provide the latter with the annular angle iron 15 which may be riveted or otherwise secured thereto, and to the inner surface of the wall 10, I 100 secure the lower ends of the arms 16, which have the upper inwardly deflected terminals 17, upon which the conical shaped roof or baffle 18 is supported.

19 designates uprights having the feet 20, which are secured to the roof 18 and the upper terminals 21, upon which is supported 105 the perforated plate or conical or dished

water distributing device, which is provided with the ports 23 therein.

24 designates an inlet pipe for water or the like which is discharged through the 5 outlet 25 upon the perforated member 22.

26 designates an inwardly extending upper annular ring or flange serving as a water baffle having the central opening 27 which is secured to the upper end of the 10 outer casing 2 preferably by means of the outer annular, angular ring 28, which is riveted or otherwise secured to the upper outer end of the casing 2.

15 The interior surface of the annular casing 2 is reinforced at various intervals by means of the angular uprights 28, which are spaced apart as seen in Figure 2, and it will be evident that a very strong, rigid and durable structure is provided which can 20 be cheaply manufactured and assembled by using standard rolled metal shapes.

29 designates a manhole opening in the bottom member or wall 3 above which is the cover 30 which is secured in any suitable manner, as will be understood from the 25 left hand portion of Figure 1.

30 The triangular shaped portion between the horizontal bottom wall 3 and the conical wall 5 may be further braced or reinforced by brackets of any suitable construction, as indicated at 31.

The operation is as follows:—

35 Assuming the parts to be assembled as seen in Figure 1 and the cupola or other furnace to be functioning in the usual manner, it will be understood that the fumes, gases, oxides, carbon and the like will be issuing through the stack 1.

40 Water having been admitted through the pipe 24, will fall upon the perforated plate 22 and will flow through the perforations and over the outer peripheral edge thereof onto member 18. A film is formed by the 45 water dripping from the edge of member 18, through which film the fumes issuing from the stack 1 must pass, it being apparent that the outer peripheral edge of the roof member 18 overhangs both the top 50 of the stack 1 and the outer edge of the annular angle iron or flange 15.

55 The sparks, oxides, carbon and other products of combustion will first impinge on the bottom of the baffle 18 and then be deflected laterally towards and through the liquid curtain, and will be arrested by said vertical curtain or wall of water and then precipitated into the annular chamber 14 and will automatically flow therefrom 60 through the port 7 and pipe 8 to any desired point.

In case the water level within the annular chamber 14 should arise to the height indicated by the port 9, seen at the right of Figure 1, it will be apparent that an effective overflow will be provided therefor.

The purified fumes, gases and the like, after passing through the curtain of water flowing over the peripheral edge of the member 18, pass to the atmosphere through the final central exit opening 27, the deleterious 70 impurities being trapped in the annular chamber 14.

Upon the removal of the manhole cover 30, access can be readily had to the chamber 14, as is evident.

75 It will consequently be seen from the foregoing construction that I have provided a novel and effective means, whereby sparks, oxides, carbons and the like will be entrapped and eliminated from the fumes 80 emitted from the stack to which my invention is applied.

85 In the construction seen in Figure 3, I have shown a device wherein the roof member 18 and its supports 16 conform to the structure seen in Figure 1, as well as the uprights 10 supported upon the roof member 18.

90 In lieu of the perforated conical or dish-shaped roof 22, seen in Figure 1, I may employ the conical solid member 32 against the bottom of which the incoming water is discharged through the outlet 33 which is attached to the water supply pipe 34.

95 It will be apparent that the principle of my invention is the same in both cases, since the water impinging on the member 18 will flow therefrom in the shape of an umbrella like curtain or wall in both constructions, 100 seen in Figures 1 and 3 and will effectively purify the fumes or gases which are discharged from the stack 1 and impinge upon the bottom of the roof member 18.

105 It will be apparent that while I have shown the outer casing 2 as having a circular or annular contour, the same may have any other desired contour without departing from the spirit of my invention, and while I have shown the preferred manner of assembling the bottom member 3 and the upright walls 2 and 10 and the roof member 18, so that a structure possessing the requisite rigidity and durability may be produced, it will be apparent that these elements may be assembled in other ways 110 without departing from the spirit of my invention.

115 It will be apparent that the baffle 18 in both the constructions seen in Figures 1 and 3 serve to deflect laterally the fumes issuing from the stack and that said baffle is kept cool in the construction seen in Figure 1 by the water dropped thereon through the ports 23 and in the construction seen in Figure 3, the baffle 18 is kept cool by the water falling thereon. In both the constructions seen in Figures 1 and 3, the water is deflected from the peripheral edge of member 18 in the shape of an umbrella like curtain through 120 which the fumes must pass before making 125

their final exit from the arrester, the upper baffle 26 preventing the escape of any water.

It will now be apparent that I have devised a novel and useful spark arrester and smoke eliminator, which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention what I claim as new and desire to secure by Letters Patent, is:—

1. In a device of the character stated, an outer casing, a horizontal base member secured thereto, an inner, vertical wall secured to said horizontal base member, a conical roof member supported in fixed position above and overhanging said inner, vertical wall, an inverted, conical, perforated water supplying device supported by spaced uprights having feet fixed to said roof member, said device being dished and having an open top, annular angle irons secured at the junction of the vertical outer and inner walls with said base member and caulked with respect thereto so as to form a water tight annular chamber, a smoke stack, and means for securing said base member and its adjuncts to said stack, in combination with an upper, inwardly and downwardly extending flange serving as a water baffle secured to said outer casing and having a central exit opening.

GEORGE J. FOX.

tion of the vertical, outer and inner walls with said base member and caulked with respect thereto so as to form a water-tight, annular chamber, a smoke stack, means for securing said base member and its adjuncts to said stack, a man-hole and a drain arranged in said base member, and an overflow arranged in said annular chamber.

2. In a device of the character stated, an outer casing, a horizontal base member secured thereto, an inner vertical wall secured to said horizontal base member, a conical roof member supported in fixed position above and overhanging said inner wall, an inverted, conical, perforated water supplying device having an open top, said water supplying device being arranged above said roof member, angle irons for supporting said water supplying device fixed upon said roof member, annular angle irons secured at the junction of the vertical outer and inner walls with said base member and caulked with respect thereto so as to form a water tight annular chamber, a smoke stack, and means for securing said base member and its adjuncts to said stack, in combination with an upper, inwardly and downwardly extending flange serving as a water baffle secured to said outer casing and having a central exit opening.
